US0D1031387S

(12) **United States Design Patent** (10) **Patent No.:** **US D1,031,387 S**
Martinez (45) **Date of Patent:** ** *Jun. 18, 2024

(54) **UTENSIL ADAPTED FOR USE WITH A FOOD STORAGE CAN**

(71) Applicant: **Stephan Ryan Martinez**, Seattle, WA (US)

(72) Inventor: **Stephan Ryan Martinez**, Seattle, WA (US)

(*) Notice: This patent is subject to a terminal disclaimer.

(**) Term: **15 Years**

(21) Appl. No.: **29/803,053**

(22) Filed: **Aug. 10, 2021**

(51) **LOC (14) Cl.** 07-04

(52) **U.S. Cl.**

USPC **D7/669**; D7/395

(57) **CLAIM**

The ornamental design for a utensil adapted for use with a food storage can, substantially as shown and described.

DESCRIPTION

FIG. 1 is a plan view of a utensil adapted for use with a food storage can;

FIG. 2 is a side view thereof;

FIG. 3 is a bottom-back isometric view thereof; and,

FIG. 4 is a top-front isometric view thereof.

1 Claim, 4 Drawing Sheets
